US00D986215S

(12) **United States Design Patent** (10) **Patent No.:** **US D986,215 S**
(45) **Date of Patent:** **** May 16, 2023**

(54) **HEADPHONE**

(71) Applicant: **Beyerdynamic GmbH & Co. KG,**
Heilbronn (DE)

(72) Inventor: **Mirja Jörgensen**, Heidelberg (DE)

(73) Assignee: **BEYERDYNAMIC GMBH & CO.**
KG, Heilbronn (DE)

(**) Term: **15 Years**

(21) Appl. No.: **35/513,459**

(22) Filed: **Jan. 13, 2022**

(80) **Hague Agreement Data**

Int. Filing Date: **Jan. 13, 2022**

Int. Reg. No.: **DM/218488**

Int. Reg. Date: **Jan. 13, 2022**

Int. Reg. Pub. Date: **Jan. 28, 2022**

(30) **Foreign Application Priority Data**

Jul. 20, 2021 (EM) 008624738-0001
Jul. 20, 2021 (EM) 008624738-0002

Primary Examiner — Paula Allen Greene

(74) *Attorney, Agent, or Firm* — Fross, Zelnick, Lehrman & Zissu PC; Charles T. J. Weigell, Esq.

(57) **CLAIM**

The ornamental design for a headphone, as shown and described.

DESCRIPTION

1.1 is a front view of a headphone showing my new design;
1.2 is a left perspective view thereof;
1.3 is an enlarged right perspective view thereof;
1.4 is a right perspective view thereof;
1.5 is a right perspective view thereof showing the headphone in an alternate position of use;
1.6 is an enlarged left perspective view thereof; and
1.7 is a right side view thereof;
